CAN OPENER

Fred E. Leitch, Cleveland, Ohio

Application May 14, 1945, Serial No. 593,616

3 Claims. (Cl. 30—8)

1

This invention relates to can openers and more particularly to one that will open tin cans, pull bottle caps, unscrew screw bottle caps, punch milk cans and the like, and beat eggs.

An object of this invention is to provide a can opener that maintains the cutter in close contact with the can while the can is being cut.

Another object of this invention is to provide a support for the cans which are being opened and bowls and the like when eggs are being beaten.

With the above and other objects in view, as will be apparent from the following description, this invention consists in the construction, combination and arrangement of parts all as herein-after claimed and illustrated in the accompanying drawings wherein:

Fig. 1 is a side elevation partly broken away of an embodiment of the invention.

Fig. 2 is a view of the opposite side showing the can punching and screw top opening mechanism in operation and a bottle cap in position to be removed from the bottle to which it is attached.

Fig. 3 is a view of the same with the can cutting mechanism in operation.

Fig. 4 is a top plan view thereof.

Fig. 5 is a sectional view on the line 5—5 of Fig. 1.

Fig. 6 is a sectional view on the line 6—6 of Fig. 3.

Fig. 7 is a sectional view on the line 7—7 of Fig. 2.

Fig. 8 is a view of the egg beater attachment.

Fig. 9 is a sectional view on the line 9—9 of Fig. 8.

Fig. 10 is a sectional view on the line 10—10 of Fig. 1.

Fig. 11 is a sectional view on the line 11—11 of Fig. 1 and

Fig. 12 is a detailed view of the locking mechanism for the shelf.

Referring more in detail to the drawings, 20 indicates the main supporting framework of the device which, as shown, comprises a one-piece substantially rectangular plate having a flange 22 extending outwardly at right angles from the bottom edge thereof.

The rear edge 24 of the framework 20 is adapted to be received in the bifurcated end 26 of a supporting rod 28 and is retained therein by means of soft rivets 30 or other similar fastening means.

The rod 28 is supported on a wall or other suitable support 32 by means of an upper bracket 34 and a lower bracket 36. The end marginal portions of the brackets may be turned downwardly 35 as

2

at right angles thereto as at 38 and 40 respectively and serve to attach the device to the support 32 as shown by means of screws 42 or the like.

The brackets are of a substantial nature and the bracket 34 is provided with a hinged portion 44 which is connected to the rear portion 46 of the bracket 34 by means of a hinge 48, the hinge 48 being connected to the bracket 34 by rivets 47 or similar means. A coil spring 50 on the pindle 51 of the hinge 48 retains the portion 44 in a normally longitudinal position. The end marginal portions of the portion 44 may be turned upwardly at right angles thereto as at 52 to retain the framework 20 in a position at right angles to the support 32 by means of a recess 54 in the upturned portions 52 which coact with the flanged end 22 of the framework 20. When it is desired to swing the framework 20 into an inoperative position against the support 32, the portion 44 is depressed (as shown in dotted lines in Fig. 1), by means of a finger hold 56 extending forwardly of the portion 52 and formed integral with the portion 44.

Mounted for vertical adjustment on the supporting rod 28 is a can, bowl, or the like support or shelf 58. The shelf 58 is made of one piece and is bent upon itself to form a circular sleeve 60 which is adapted to receive the rod 28. The duplicate portions 62 are formed with depending substantially triangular flanges 64 which are retained in face to face relation with each other by means of soft rivets 65 or similar fastening means. Extending at right angles thereto and in parallel relation to each other are the shelf portions 66.

35. The sleeve 60 is provided with a V-slot 68 to receive the locking key 70. The key 70 is provided with the opening 72 (Figure 10) for mounting on the rod 28, and duplicate forwardly extending projections 74 which form a slot 76 which receives the flanges 64 therein. The key 70 will lock the shelf 58 in any desired position on the rod 28 in relation to the height of the article to be supported and the framework 20.

The forward marginal edge of the lower bracket 45 36 may be turned upwardly at right angles thereto as at 78 to retain the shelf 58 in a position at right angles to the support 32 by means of a recess 80 in the upturned portion 78 which coacts with the flanges 64 of the shelf 58.

50. The rod 28 is retained in the aligned openings 82 of the brackets 34 and 36 by means of a cotter key 84 in the opening 86 in the lower end 88 of the rod 28.

Referring to the can opener and other mechanism this includes a knife 90 having a sharp-

ened edge 92 and a point 94 adapted to pierce the can and a feed wheel 96 having teeth 98, similar to saw teeth. See Figures 2 and 3.

The knife 90 is secured to a pivoted plate 100 by screws 102 or other similar fastening means and the plate is pivoted to the framework 20 by means of a pivot pin 104 which may be a screw and nut 105 as shown, or other similar pivot means.

The plate 100 has outturned duplicate projections 106 which extend outwardly on opposite sides of the knife 90 and act as guides in relation to the knife 90 for abutting the upper rolled rim of the can A shown in dotted lines in Fig. 3.

The plate 100 lies flat against the framework 20 and is provided with an apertured projection 108 for connection to an eccentric wheel 110 by means of a pivot pin or screw 112 retained in position by a nut 113 (Figure 1) or similar pivoting means. The wheel 110 is rotatably mounted in an opening 114 in the framework 20.

A handle 116 having a knob 117 thereon lies flat against the opposite side of the framework 20 and is connected to the wheel 110 by means of a pivot 118 which in this instance is a screw retained in position by a nut 119, but may be any type of pivoting means.

The eccentric motion is obtained by also attaching the handle 116 on the pivot 112.

Therefore by forward and rearward movement of the handle 116 the plate 100 and knife 90 is brought into and out of cutting engagement with the can A.

Since the plate 100 constitutes a movable mounting for the knife 90 it is held in abutment with the can A by a coil spring 120 having one end operatively engaging the opening 122 in the rear projection 106, and the other attached to an apertured outturned projection 124 which is struck out of the framework 20.

The pivot pin 104 is mounted for sliding movement in a slot 126 in the framework 20 and is held in abutment with the lower end of the slot 126 by a coil spring 128 having one end operatively engaging the pin 104 and the other end attached to an apertured outturned projection 130 which is struck out of the framework 20.

The feed wheel 96 is mounted on an axle 132 which is burred at its outer end to prevent displacement of the wheel 96. The axle 132 is supported in a bearing 134 (Figure 5) welded to the framework 20 on the opposite side to the feed wheel 96.

The opposite end of the axle 132 is provided with a gear wheel 136 and a crank 138 having a suitable handle 140 is secured to the gear wheel 136 by rivets 142 or similar fastening means. The end of the axle is threaded to receive the complementary threaded nut 141 to retain the gear wheel 136 thereon.

When the handle 116 is moved rearward and assumes the position shown in Fig. 1, the knife 90 and plate 100 are out of engagement with the can A but when moved forward to assume the position in Fig. 3 the knife 90 and plate 100 are in cutting engagement with the can A.

In its rearward movement a substantially square shaped projection 115 on the handle 116 coacts and contacts with the inturned end 144 of a vertical can punch 146. The end 144 is externally threaded to receive a complementary nut 148 to retain the punch 146 in a vertical slot 150 in the framework 20. The punch 146 is reciprocably mounted in an apertured plate 152 which is secured to the flange 22 of the frame-

work 20 by screws 154 or other fastening means. A coil spring 156 encircles the punch 146 to return the punch to inoperative position, one end of the spring 156 bearing against the end 144 and the opposite end bearing against the plate 152.

During its downward movement to punch the can B as shown in Fig. 2 the end 144 contacts and coacts with an arcuate slot 158 in a curved plate 160 which is pivoted on the framework 20 by means of a pivot pin 162 which in this instance is a screw retained in position by a nut 161, but can be any type of pivoting means desired. A washer 163 is mounted on the end 144 to coact with and prevent the jamming of the plate 160 during the movement thereof.

The plate 160 pivots forwardly and in so doing the saw teeth 164 on the edge of the plate 160 slides over an opening 166 provided in the framework 20 adjacent the edge 24 thereof.

The edge 168 of the opening 166 is V-shaped and provided with saw teeth 170.

The point of the V-shaped edge 168 extending toward the rod 28.

Therefore, as the plate 160 pivots forwardly the teeth 164 thereon and the teeth 170 coact to clamp a screw cap C of a bottle and thereby unscrew the cap C from the bottle.

The downward action of the punch 146 and the forward action of the plate 160 are therefore simultaneous with the movement of the handle 116 when moved in a rearward direction to disengage the knife 90 and plate 100 from the can A.

The gear wheel 136 is adapted to mesh with intermeshing gear wheels 172 to which are secured similar intermeshing egg beaters 174, (Figure 8) and the gears 172 and beaters 174 are rotatably mounted on the usual supporting members 176 (Figure 5) which are welded to an L-bracket 178 which in turn is welded to a supporting arm 180.

The arm 180 has an upturned T-shaped projection 182 on the end 183 thereof, Figure 9, which is adapted to be received in the T-shaped slot 184 in the framework 20.

The lower edge 186 of the arm 180 is parallel with the lower edge 21 of the framework 20 and the upper edge 188 of the arm 180 is received in a recess 131 in the projection 130 (Figure 5).

The opposite or free end 190 of the arm 180 comprises an enlarged portion 192 in which is rotatably mounted the shaft 194 of a locking key 196, the axle of which is threaded at its outer end to receive a complementary threaded nut 198 (Figure 1) and the end is burred to prevent the removal of the nut 198. An eccentric 200 is mounted on the shaft 194 and is adapted to lock the free end 190 of the arm 180 in face to face engagement with the framework 20 by being positioned in the opening 202 (Figure 2) in the front end 23 of the framework 20.

Thus when the crank 138 is rotated the gear wheels 172 will mesh with the gear wheel 136 on the crank 138 causing the beaters to be rotated in the usual manner.

The opening 202 being in the end 23 of the framework 20 is open for part of its circumference, the upper termination of the opening being provided with the eccentric contacting and locking edge 204 which extends beyond the end 23 of the framework 20 and terminates in a point 206, the lower termination of the opening 202 forms a point 208 and these form the releasing means for the eccentric 200 as well as a bottle opener as shown in Fig. 2.

The bearing 134 is of a sufficient size to permit the meshing of the gears 136 and 172 without hindering or preventing the rotation thereof.

The operation of the device is as follows: The operator places the can A in the guide groove 210 in the flange 22 of the framework 20 so that the top edge of the rim contacts the guide 106 and the feed wheel 96 contacts the lower edge of the rim of the can. The handle 116 is then moved forward actuating the plate 100 and causing the knife 90 to puncture the top of the can A. The upper rim as stated being properly positioned by the groove 210 and guides 106. The mechanism is so designed that the plate 100 shall be maintained in contact with the can at all times by the spring 120 so that the knife 90 is always held in cutting position and the plate 100 presses the can against the feed wheel 96 to prevent the slipping thereof.

As has been previously explained the forward and rearward movement of the handle 116 will act to punch cans or remove screw caps from bottles and it is thought that the action of the beaters will be apparent.

It will be understood, therefore, by those skilled in the art that the embodiment of the invention herein disclosed accomplishes the objects of the invention. It also has uses and advantages other than those herein particularly referred to, also various changes and modifications may be made without departing from the spirit of the invention, and since the embodiment disclosed herein is only illustrative of the device, the invention is not to be understood as restricted thereto since this may be modified within the scope of the appended claims without departing from the spirit and scope of the invention.

Having thus described the invention, what is claimed as new and desired to be secured by Letters Patent is:

1. A device of the character described comprising a framework constituting a one piece substantially rectangular plate having a flange ex-

tended outwardly at right angles from the bottom edge thereof, a supporting rod for said framework, having an upper bifurcated end in which said frame is mounted intermediately thereof, means for securing said frame in said bifurcated end, a bracket for receiving said rod, means on said bracket for retaining said framework in right angular relation to said bracket, means for retaining last said means in relation to said framework, a plate pivotally mounted on said framework, a knife on said plate, a feed wheel coacting with said knife, an eccentric mounted in said framework, said plate being pivotally attached on one side of said framework to said eccentric and a handle on the other side of said framework attached to said eccentric and a crank having a handle for rotating said feed wheel.

2. The invention as described in claim 1, wherein guides for positioning a can in relation to said knife are provided on said plate.

3. The invention as described in claim 1, wherein tensioning means are connected to said plate to force said plate against a can positioned for cutting engagement with said knife.

FRED E. LEITCH.
